UNITED STATES PATENT OFFICE.

ERNEST D. CLARK, OF WORCESTER, MASSACHUSETTS.

RAZOR-STROPPING MACHINE.

Application filed January 5, 1921. Serial No. 435,179.

To all whom it may concern:

Be it known that I, ERNEST D. CLARK, a citizen of the United States, residing at Worcester, in the county of Worcester and 5 Commonwealth of Massachusetts, have invented a new and useful Improvement in Razor-Stropping Machines, of which the following, together with the accompanying drawings, is a specification.

10 My invention relates to razor stropping machines of the type in which a blade holder is moved with respect to a strop, in order to sharpen the edge of a blade carried by the holder.

15 Razor stropping machines of this type have heretofore been constructed for moving the blade transversely across the face of the strop, at the same time that the blade is moved longitudinally along the strop. These 20 movements have been obtained simultaneously by various mechanisms actuated by the relative movement between the machine and the strop, and such machines have been successful in obtaining a diagonal movement 25 of the blade with respect to the strop in imitation of the stroke employed when sharpening a blade by hand.

Such prior machines, however, have been 30 open to the defect that they fail to imitate the complete movement which is imparted to a blade when it is desired to sharpen both sides thereof. It is well known that when it is desired to sharpen a razor, or any other cutting blade, that one edge is first drawn 35 diagonally across the strop or stone and then at the end of this stroke the blade is first shifted across the strop and then turned over before the other cutting edge is drawn diagonally across the strop, but in the same 40 direction in which the blade was first drawn. This cycle of movement is always repeated in order to insure that the flow of metal which occurs along the cutting edge will always be in one direction. Thus, in sharpening 45 a knife this flow of metal is always in the direction of the point.

In all prior razor stropping machines, the movements have been such that the metal is first drawn in one direction on one side of 50 the blade and then in the opposite direction on the other side of the blade, thus departing from the usual method of stropping, and necessarily failing to obtain the best results. This is due to the fact that in prior machines 55 the blade always follows the same diagonal

path across the strop, but in opposite directions.

By my invention I propose to provide a novel form of razor stropping machine in which the blade is first drawn diagonally 60 across the strop so that the metal is drawn in a given direction, and then upon reversing the blade it is so shifted with respect to the strop that the metal is still drawn in the same direction upon the return diagonal 65 movement of the blade with respect to the strop. In this way it is possible to obtain a complete cycle of movement closely approximating that which occurs when a blade is sharpened by hand. These and other advantageous features of my invention will herein-after more fully appear, reference being had 70 to the accompanying drawings, in which—

Figure 1 is a view in end elevation of a machine embodying my invention, the end 75 plate being removed.

Figure 2 is a longitudinal sectional view along the line 2—2, Fig. 1.

Figure 3 is a view similar to Fig. 1, showing the position of the parts occupied when 80 the machine is moved in the opposite direction from that shown in Fig. 1.

Figure 4 is a longitudinal sectional view along the line 4—4, Fig. 3.

Figures 5 to 8, inclusive, are diagrammatic 85 views showing the movements of the blade holder as the machine is moved back and forth with relation to the strop.

Similar reference letters refer to similar 90 parts in the different figures.

Referring to Figs. 1 and 2, the machine comprises a frame 1 within which are journaled strop rollers 2, 3, and 4. The frame 1 is provided at its ends with openings 5 for receiving the strop 6 which passes over the rollers 2 and 4 and under the roller 3. The frame 1 is also provided with a handle 7 by means of which the frame 1 may be moved back and forth upon the strop 6 with one hand, while the latter is held taut with the other hand.

A worm shaft 8 is journaled in the frame 1 immediately above and parallel to the roller 3 and is connected to the shaft of the roller 3 by means of gears 9 and 10. A blade holder shaft 11 is journaled in the frame 1 immediately above and parallel to the worm shaft 8, and is connected to the shaft of the roller 4 by means of cranks 12, 13, joined by a link 14. A blade holder 15 is slidably 110

keyed on the shaft 11 and is provided with a radially extending pin 16 that is adapted to engage in threads 17 provided on the left hand portion of the worm shaft 8, as shown in Fig. 2. The blade holder 15 may be of any suitable form to receive a blade 18.

When the frame 1 is moved upon the strop 6 in the direction indicated by the arrow in Fig. 1, the roller 4 is rotated in a clockwise direction, and the shaft 11 is rotated in the same direction to cause the blade 18 to engage the strop 6. This same movement of the frame 1 also causes the roller 3 to be rotated and thereby drive the worm shaft 8 in the direction indicated by the arrow, through the gears 9 and 10. As the pin 16 is in engagement with the thread 17 on the shaft 8, the blade holder 15 will be moved from left to right, as indicated, 20 as the frame 1 is moved upon the strop 6 in a direction away from the user. As the blade holder 15 is moved transversely it compresses a spring 19 surrounding the shaft 11, for a purpose to be hereinafter described. 25 The movement of the blade holder 15 as the frame 1 is moved the full length of its stroke away from the user is indicated diagrammatically in Fig. 5, the spring 19 being shown as fully compressed at the end of this stroke.

The frame 1 having reached the end of its stroke away from the user, the handle is then pulled in the opposite direction as indicated in Fig. 3. When this movement begins, the roller 4 is turned in a counterclockwise direction, as indicated, which causes the shaft 11 to be turned in the same direction to lift the blade 18 from the right hand portion of the strop 6, and to turn it over 35 into engagement with the strop 6 on the opposite side of the shaft 11. As the blade holder 15 is turned over, the pin 16 is moved out of engagement with the threads 17 so that the compressed spring 19 is free to shift 40 the blade holder 15 back to its original position, as indicated by the arrow in Fig. 6. This shifting movement occurs almost instantaneously and before the blade holder 15 has been completely turned over by the 45 operation of the cranks 12 and 13 and the link 14. As the blade holder 15 returns to its original position, a pin 20 located diametrically opposite to the pin 16 at the other end of the holder engages threads 21, provided at the right hand end of the shaft 8. The threads 21 are of opposite pitch with 50 respect to the threads 17 which were previously engaged by the pin 16. The position of the blade holder 15 at the end of the 55 shifting movement is shown diagrammatically in Fig. 7.

As the frame 1 is pulled in the direction of the user, as indicated by the arrow in Fig. 3, the blade 18 is held in engagement 60 with the left hand portion of the strop by

the tendency for the shaft 11 to be turned by the roller 4, and at the same time, the shaft 8 is rotated in the opposite direction from that in which it was rotated before, as indicated by the arrow in Fig. 4. This rotation of the shaft 8 causes the blade holder 15 to again be shifted from left to right as the frame 1 is pulled toward the user. This is due to the fact that the threads 21 have a pitch opposite to the threads 17 and consequently the reversal of rotation of the shaft 8 causes shifting movement of the blade holder 15 in the same direction as before. The path of movement of the blade holder 15 as the frame 1 is moved from one end of its stroke toward the user, to the other, is indicated diagrammatically in Fig. 7, the spring 19 being shown as compressed at the end of this stroke. Obviously the blade holder 15 will again be shifted from right to left by the spring 19 as soon as the frame 1 is started on its return stroke away from the user.

From the foregoing, it is obvious that the blade 18 will be repeatedly moved through the same cycle so long as the frame 1 is moved back and forth on the strop. One complete cycle of movement is indicated diagrammatically in Figs. 5 to 8, inclusive, from which it appears that the blade is always moved diagonally across the strop 6 from left to right, as indicated by dotted lines in the diagrams. Consequently the metal is always drawn in the same direction as first one side of the blade and then the other is presented to the strop, by the operation of the shifting device. It is obvious that the above described cycle of movements closely approximates the movement imparted to a blade that is being stropped by hand, and in view of the fact that the movement of the blade in my machine is always uniform, it is believed that even better results can be obtained by the use of my machine than by hand stropping.

While I am aware that various machines have heretofore been employed for obtaining a diagonal movement of the blade across the strop, it is believed that my improved machine is the first to duplicate the actual movements of hand stropping, whereby the metal along the cutting edge of the blade is always drawn in the same direction. While I have shown a specific arrangement of instrumentalities for obtaining the above described advantageous results, it is obvious that other instrumentalities may be as readily employed, and I desire therefore that only such limitations be imposed upon my invention as come within the scope of the appended claims.

I claim,

1. In a razor stropping machine, the combination with a strop, and a blade holder longitudinally movable thereon, of means

for imparting transverse movement to said blade holder always in the same direction across the strop as said holder is moved back and forth in engagement with the 5 strop, whereby resulting diagonal movements of said holder on the strop are in different paths.

2. In a razor stropping machine, the combination with a strop, and a blade holder 10 longitudinally movable thereon, of means for imparting transverse movement to said blade holder as it is moved back and forth on the strop, and further means for shifting the blade holder at the end of each longitudinal 15 movement in a given direction across the strop, whereby resulting diagonal movements of said holder across the strop are always in the same direction.

3. In a razor stropping machine, the combination with a strop and a blade holder 20 longitudinally movable thereon, of means for imparting transverse movement to said blade holder as it is moved back and forth on the strop, and further means for simultaneously shifting said holder from one side 25 of said strap to the other and turning over said blade holder at the end of each longitudinal movement across the strop.

4. In a razor stropping machine, the combination with a strop, a blade holder movable on said strop, and a rotatable shaft provided with threads of opposite pitch for imparting transverse movement to said blade holder as it is moved longitudinally on said strop, of means for shifting said blade 30 holder bodily across the strop at the end of each longitudinal movement thereon, whereby threads of opposite pitch impart transverse movement to said holder as the latter is moved in opposite directions on said 35 strop.

5. In a razor stropping machine, the combination with a strop a blade holder movable on said strop and having projections and a rotatable shaft provided with right 40 hand and left hand threads for causing movement of said blade holder across said strop as the latter is moved longitudinally thereon, of means for shifting the blade holder bodily across the strop and turning 45 it over at the end of each longitudinal movement thereon to bring said projections into engagement with first the right hand and then the left hand threads on said shaft. 50

ERNEST D. CLARK.
